UNITED STATES PATENT OFFICE.

WILLIAM H. GREENLEAF, OF HARTFORD, CONNECTICUT, ASSIGNOR TO THE CONNECTICUT ELECTRIC CLOCK COMPANY, OF HARTFORD, CONNECTICUT, A CORPORATION OF NEW YORK.

TIME-CONTROLLED MECHANISM.

1,388,858.

Specification of Letters Patent. Patented Aug. 30, 1921.

Application filed March 29, 1920. Serial No. 369,575.

To all whom it may concern:

Be it known that I, WILLIAM H. GREENLEAF, a citizen of the United States, residing at Hartford, in the county of Hartford and 5 State of Connecticut, have invented certain new and useful Improvements in Time-Controlled Mechanism, of which the following is a specification.

This invention relates to time controlled 10 mechanism. The title selected is merely a convenient one. When the mechanism is used in the art of time-controlling devices, it may take the form for illustration of a self-winding time-piece such for instance as 15 a clock. I have a number of motives in view among them being the production of an article which is compact, which numbers relatively speaking, a small number of parts, being however accurate and susceptible of in- 20 expensive manufacture.

In the drawings accompanying and forming part of the present specification I have shown in detail one of the several forms of embodiment of the invention which I will 25 set forth fully in the following description. I am not restricted to this disclosure. I may depart therefrom in several respects within the scope of the invention defined by the claims following said description.

30 Referring to said drawings:

Figure 1 is a rear face view partly in section on the line 1—1 of Fig. 2 looking in the direction of the arrows.

Fig. 2 is an elevation as seen from the 35 right in Fig. 1.

Figs. 3 and 4 are views on larger scales partly diagrammatic and showing certain controlling parts in different positions.

Like characters refer to like parts through- 40 out the several views.

While in effect I have observed that one or more of the features of the invention can be utilized in various ways they are of particular utility however when incorporated as shown in a clock. As part of this organization is an escapement and train of gears which may be of the kind found in time-pieces. An element of the clock work 45 is the main arbor 2 supported between the front and back movement plates 3 and 4. Between the arbors is the gear train 5. The main arbor is intermittently operated at de- 50 sired intervals, for instance one minute apart, by suitable means such as pawl and

ratchet mechanism the ratchet wheel of 55 which is denoted by 6 and the pawl by 7. In the construction shown it is clear that the ratchet wheel 6 has sixty teeth in its periphery. The pawl is operatively connected with the armature 8 of the magnet 9. The 60 armature 8 practically of yoke or inverted form being in effect like that shown in Letters Patent Number 1,263,554 issued to me October 23, 1918, and to which reference 65 may be had. It will be clear that upon each half stroke of the armature 8 the pawl 7 is active for feeding the ratchet wheel 6 a distance agreeing to the space between two of its teeth. The magnet 9 is attached in some convenient way to the rear face of the 70 back movement plate 4. The armature 8 is pivoted at 10 near the junction of its short side branch and its cross branch, to the back movement plate or to a bracket thereon. To this short branch is connected one end of a 75 spring 11 the other end of the spring being fastened to some suitable fixed part. The magnet acts to impart a swing in one direction of the armature 8, opposite movement thereof being brought about through the 80 pull of the spring 11 conditioned to insure this function on the opposite movement of the armature. In Fig. 1 the armature 8 is shown as being against the magnet by full lines having been moved to this position by 85 the pull of the magnet. During such motion the spring 11 was stretched and at the conclusion of it the pawl 7 engages behind a tooth of the ratchet wheel. About the time this action takes place as I will later set 90 forth, the magnet is deenergized so that the stretched spring 11 pulls the armature to the dotted line position in said Fig. 1 and thus causes the pawl 7 to feed the ratchet-wheel 6 a distance equaling one tooth of the 95 ratchet wheel and as a consequence effects a like result with the time controlled mechanism between the front and rear movement plates 3 and 4 in the manner quite fully set forth in my issued patent to which I have 100 already referred.

The back movement plate 4 as shown sus- 105 tains in some suitable way a framing as 12 to which is in fact connected the magnet 9, the armature pivot 10 also being supported by this framing 12. The framing 12 also sustains a contact 13 shown as being of spring type the contact 13 however being in-

sulated from the framing as shown clearly in Figs. 3 and 4. The base or butt portion of the contact which is desirably of spring or yieldable type is electrically connected with 5 the magnet 9 the latter in turn being connected with a source of electrical energy as the battery 14 which is in turn electrically connected with the frame 12 as clearly shown in both Figs. 3 and 4. The contact 13 has 10 on its inner free side the head or enlargement 15 constituting the active portion thereof.

This head 15 coöperates with a switching member which is of some suitable construction, the lever 16 acting satisfactorily in this connection and being fulcrumed or pivoted as at 17 at its base to the framing 12. It may be well to note that the switching member 16 is moved to circuit breaking position by 20 the action of the armature when the magnet is energized, being moved toward circuit closing position in some convenient manner, as by the spring 18 fastened at its base to the framing 12 and the free end of which is 25 in the form of a projection 19 coöperative with the back straight face 20 of the switching lever 16 shown as being in circuit closing position in Fig. 4 by dotted lines. The free or forward end of the switching lever 30 has set thereinto the brush member 21 coöperative with the contact head 15. It should be noted at this time that the brush member 21 has merely an engagement with the head 13 as distinguished from a rocking sliding 35 contact therewith. In this respect the switching lever 16 differs strikingly from the theoretically corresponding part in Letters Patent 1,164,602 issued to me December 14, 1915. As a matter of fact the present construction is radically different from that of my prior patent in many particulars. Another point is the lever 16 moves in one direction or toward circuit making position for instance by the power of spring means. 40

45 On the framing 12 is mounted a sear member or catch of suitable character, the lever 22 answering satisfactorily in this connection, said lever being pivoted as at 23 to the framing 12. One arm of the lever has a 50 catch finger as 24 coöperative with a lateral projection 25 on what is shown as the upper side of the switching or circuit controlling lever 16. The tail or long rear arm of the sear member or catch 22 is coöperative with 55 a controlling member such as the stud or extension 27 on the longer branch of the armature 8. The framing also has fastened thereto one end of the elongated spring 28 the projection 29 of which at the upper end 60 thereof, bears against the lug 30 of the sear member 22 to hold the long arm or tail branch 26 of said sear member in engagement with the stud 27.

It will be assumed that the coil of the 65 magnet 9 is in an electric circuit such for in-

stance as that described, and that the brush or engaging portion 21 is in contact with the head 15 of the contact spring 13. In this event the magnet 9 is energized and attracts its armature from the dotted line position 70 in Fig. 1 to the full line position shown therein and as a result stretching the spring 11 constituting a suitable motor. As the short arm or branch of the armature is thus moved it carries the pawl 7 therewith, the latter engaging behind a tooth of the ratchet wheel 6. As the armature is attracted the stud 27 will fall away from the long branch 80 of the sear member 22 and on the downward movement of the stud 27 this stud will engage against the flat surface 31 of the switching member 16 and thus swing the switching member downward and as a result cause the brush or contacting portion 21 to be disengaged from the head 15 of the spring contact 13 as shown in Fig. 3. At the same time the projection 25 of the sear member 22 will engage over the upper flat surface of the projection 25 and thus momentarily hold the switching or controlling member 90 down having on such downward movement promptly broken the circuit. When the circuit is broken the conditioned spring 11 will by acting against the armature 8 swing said armature from the full line position to the 95 dotted line position on the right in Fig. 1. On this particular motion of the armature the ratchet wheel 6 is fed around a distance of one tooth by the pawl 7. As the armature swings outward in the manner indicated, the 100 stud 27 is moved upward and engaging the longer arm of the sear or catch member 22 will swing the catch finger 24 from the projection 25 and as a result free the switching or controlling member 16 so that the spring 105 18 can again act upon the switching member 16 to cause its operative portion 21 to engage the head 15 and close the circuit and repeat the cycle.

What I claim is:

1. The combination of time controlled mechanism involving an arbor, a ratchet wheel associated with said arbor, a magnet, an armature for the magnet, the latter when energized acting to attract its armature, 115 means for operating the armature in an opposite direction, when the magnet is deenergized, a pawl for actuating said ratchet wheel, operated by the armature, a catch member, a circuit controlling member, the 120 armature having controlling means to engage under the catch member and to free the catch member when the magnet is deenergized, the controlling means on such motion also engaging the circuit controlling 125 member to move the same to circuit breaking position, means acting against the catch member to cause it to momentarily hold the circuit controlling member in circuit breaking position, a contact, and means for causing 130

the circuit controlling member to engage said contact, after the catch member has been tripped by said controlling means.

2. The combination of time controlled mechanism involving an arbor, a ratchet wheel associated with said arbor, a magnet, an armature for the magnet, spring means for operating the armature in an opposite direction when the magnet is deenergized, 5 a pawl for actuating said ratchet wheel, operated by the armature, a catch member, a circuit controlling member, the armature having controlling means to engage under the catch member and to free the catch member 10 when the magnet is deenergized, the controlling means on such motion also engaging the circuit controlling member to move the same to circuit breaking position, means acting against the catch member to 15 cause it to momentarily hold the circuit controlling member in circuit breaking position, a contact, and a spring for causing the circuit controlling member to engage said contact, after the catch member has been 20 freed by said controlling means.

3. The combination of time controlled mechanism involving an arbor, a ratchet wheel connected with said arbor, a magnet, an armature for the magnet, the latter when 25 energized acting to attract its armature, means for operating the armature in an opposite direction when the magnet is deenergized, a pawl for actuating said ratchet wheel, operated by the armature, a catch 30 member, a circuit controlling member, the armature having a projecting stud to engage under the catch member and to free the catch member when the magnet is deenergized, the stud on such motion engaging the circuit controlling member to move the same to circuit breaking position, means acting against the catch member to cause it to momentarily hold the circuit controlling member in circuit breaking position, a contact, and means for causing the circuit controlling member to engage said contact, after the catch member has been freed by said 35 stud.

4. The combination of time controlled mechanism involving an arbor, a ratchet wheel associated with said arbor, a magnet, an armature for the magnet, the latter when 40

energized acting to attract its armature, means for operating the armature in an opposite direction when the magnet is deenergized, 55 a pawl for actuating said ratchet wheel, operated by said armature, a catch member, a circuit controlling member, the armature having a stud to engage under the catch member, and to free the catch member when the magnet is deenergized, the stud on such motion acting against the circuit controlling member to move the same to circuit breaking position, a spring acting 60 against the catch member to cause it to engage and momentarily hold the circuit controlling member in circuit breaking position, a contact, and a spring for causing the circuit controlling member to engage said contact, after the catch member has been 65 freed by said stud.

5. The combination of time controlled mechanism involving an arbor, a ratchet wheel associated with the arbor, a magnet, an armature for the magnet, the latter when 70 energized acting to attract its armature, a spring for operating the armature in an opposite direction when the magnet is deenergized, a pawl for actuating said ratchet wheel, operated by said armature, a catch 75 member, a pivotally mounted circuit controlling member, the armature having a stud to engage under the catch member and to free the same when the magnet is deenergized, the stud on such motion also engaging the circuit controlling member to move the same to circuit breaking position, a spring acting against the catch member, the circuit controlling member having a lateral projection, a spring to operate said 80 catch member to cause it to engage said projection when the stud frees the catch member to thereby momentarily hold the circuit controlling member in circuit breaking position, a contact and a spring acting against 85 the circuit controlling member to cause the same to engage said contact, after the catch member has been freed by said stud.

In testimony whereof I affix by signature in the presence of two witnesses.
